UNITED STATES PATENT OFFICE

CHARLES O. COZZENS, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS

DESIGN FOR A BRIDGE FOR AN OPHTHALMIC MOUNTING

Application filed September 15, 1932. Serial No. 44,838. Term of patent 14 years.

To all whom it may concern:

Be it known that I, CHARLES O. COZZENS, a citizen of the United States, residing at Southbridge, in the county of Worcester and State of Massachusetts, have invented a new, original, and ornamental Design for a Bridge for an Ophthalmic Mounting, of which the following is a specification, reference being made to the accompanying drawing forming a part thereof.

Figure I is a front perspective view of a bridge for an ophthalmic mounting showing my new design.

Figure II is a plan view thereof.

I claim:

The ornamental design for a bridge for an ophthalmic mounting substantially as shown.

In testimony whereof, I affix my signature.

CHARLES O. COZZENS.
